DESIGN FOR A TOLL COIN OR TOKEN DEVICE FOR AUTOMOBILES

Abraham Zitenfield and Joe Weil, New York, N. Y.

Application June 21, 1947, Serial No. 139,856

Term of patent 14 years

(Cl. D52—4)

To all whom it may concern:

Be it known that we, Abraham Zitenfield and Joe Weil, citizens of the United States, residing at New York, in the county of New York and State of New York, have invented a new, original, and ornamental Design for Toll Coin or Token Device for Automobiles, of which the following is a specification, reference being had to the accompanying drawing, forming part thereof.

In the drawing

Fig. 1 is a top plan view of a toll coin or token device for automobiles, showing our new design;

Fig. 2 is a front elevational view thereof;

Fig. 3 is a side elevational view thereof with a portion of the wall broken away to disclose the contour of one of the parts; and

Fig. 4 is a bottom plan view thereof.

We claim:

The ornamental design for a toll coin or token device for automobiles, substantially as shown.

ABRAHAM ZITENFIELD.

JOE WEIL.
